[57] CLAIM

The ornamental design for a child's play table, as shown and described.

DESCRIPTION

FIG. 1 is a perspective view of a child's play table showing my new design, an opposite view being a mirror image thereof,

FIG. 2 is a top plan view thereof,

FIG. 3 is a bottom plan view thereof, and,

FIG. 4 is a side elevational view thereof, the opposite side being a mirror image.
